(57) **CLAIM**

The ornamental design for a bookmark with protruding ear, as shown and described.

DESCRIPTION

FIG. 1 is a front perspective view of a bookmark with protruding ear;

FIG. 2 is a front elevational view of the embodiment shown in FIG. 1;

FIG. 3 is a rear elevational view of the embodiment shown in FIG. 1;

FIG. 4 is a left side elevational view of the embodiment shown in FIG. 1;

FIG. 5 is a right side elevational view of the embodiment shown in FIG. 1;

FIG. 6 is a top plan view of the embodiment shown in FIG. 1;

FIG. 7 is a bottom plan view of the embodiment shown in FIG. 1;

FIG. 8 is a front perspective view in reduced scale of the embodiment shown in FIG. 1 showing my new design with a book depicted in broken lines for illustrative purposes only, forming no part of the claimed design; and,

FIG. 9 is a partial front perspective view of the embodiment shown in FIG. 1 showing my new design with a book depicted in broken lines for illustrative purposes only, forming no part of the claimed design.
